HOUSING FOR AN INDOOR LIGHT FIXTURE OR THE LIKE

George D. Cooper, 1136 Vista Place, Edmonds, Wash.

Filed May 28, 1965, Ser. No. 85,490

Term of patent 14 years

(Cl. D48—20)

FIG. 1

FIG. 2

FIG. 3

FIG. 4

FIG. 5

FIG. 1 is a front elevational view of the housing for an indoor light fixture or the like embodying the new design;

FIG. 2 is a side elevational view of the housing for an indoor light fixture or the like of FIG. 1;

FIG. 3 is a rear elevational view of the housing for an indoor light fixture or the like of FIG. 1;

FIG. 4 is a top plan view of the housing for an indoor light fixture or the like of FIG. 1 the bottom plan view being substantially a mirror image thereof; and

FIG. 5 is a front perspective view of the housing for an indoor light fixture or the like of FIG. 1.

The diagonal shade lines are representative of a reflective surface.

I claim:

The ornamental design for a housing for an indoor light fixture or the like, as shown and described.
